LANDING NET

Edward C. Walter, Orange, N. J.

Application February 18, 1931. Serial No. 516,566

6 Claims. (Cl. 43—12)

This invention relates to landing nets used by sportsmen and others.

An object of the device is to enclose the net in a shield except when it is desired to use it.

5 Another object is that the net may be readily and quickly removed from its shield and the supporting frame therefor automatically opened.

Another object is that of locking the net and frame in the shield in such a manner that they 10 cannot be unsheathed until the lock has been released.

Another object is that the device may be utilized as a wading staff.

Another object is that the device may be taken 15 apart, making it more portable.

Another object is to provide the device with means for hooking it to the harness or clothing of the user.

Another object is that the device may be 20 readily and quickly opened by use of only one hand.

Other objects will be set forth in the following specification.

The invention consists in the novel construction and combination of parts as set forth in 25 the appended claims.

In the accompanying drawing illustrating the invention:

Figure 1 is a front elevation view, showing 30 the parts coupled together and the net and frame enclosed.

Figure 2 is a front elevation view, showing the net and frame opened and shield lowered.

Figure 3 is a front elevation view similar to 35 Figure 2 but partly in section.

Figure 4 is a plan view of the upper end of the shield showing the notches therein.

Figure 5 is an elevation view in cross section of the upper end of the shield showing the 40 notches and part of the locking means.

Figure 6 is a portion of one of the frame arms showing holes through which a lacing is passed for attaching the net.

Figure 7 is an edge view of a portion of one 45 of the frame arms, shown in section and the lacing and net attached.

Figure 1 shows one form of the device and wherein 1 is the outer shield or sheath for the net 2 and frame arms 3 when they are collapsed and inserted therein. This shield 1 is preferably made of aluminum tubing so that the structure will be light in weight. It may be wound with cord to give a good gripping surface and is provided with bands 1^a 1^b 1^c which act as 50 headings for the cord windings so that they will

not push off the ends. The center band 1^b is provided with a hanger piece 4, which provides means whereby the device may be hung on a hook fastened near the left shoulder of the user.

The arms 3 which compose the net frame are 55 inserted and fastened in a socket 5, this socket 5 is, in turn, inserted and fastened in a tubular portion 6. This tubular portion is of such dimension that it will slide freely in the shield 1. The lower end of this tubular portion 6 60 acts as a socket into which is inserted, by slight pressure, a staff 7, preferably of wood with a metal end piece 7^a which nicely fits the tubular portion 6.

The staff 7 is provided with a pin 8 which will 65 enter a notch 9 in the lower end of the tubular portion 6 and prevent any relative turning movement between these parts. The pin 8 is not of greater length than the diameter of the tubular portion 6, otherwise the pin would interfere with 70 the free passage of the tubular portion 6 into the shield 1. The lower end of the staff 7 is provided with a metal cap 15 and near the lower end of the staff 7 is a band 10 so shaped as to form 75 a stop and centralizer for the shield 1 when it is pushed down thereon. The staff 7 will never be perfectly straight and it is the slight offset of stop 10 from the centre of the device 80 which will cause a friction between the parts when the shield 1 is pushed down onto the stop 10, this friction will assist in holding the device open.

The arms 3 are preferably made of spring 85 tempered material and are so shaped as to spread apart when released from the shield 1. The outer end of each arm is provided with a hole through which a leather thong or cord 11 is passed to connect the arms. One of the arms 3 is provided with a pin 12, which, when the arms are collapsed and inserted into the shield 90 1, will enter a hole 13 in the upper end thereof and will lock the frame and net therein. Slight pressure sidewise on the end of one of the arms 95 3 will withdraw the pin 12 from the hole 13, thus the shield 1 is unlocked therefrom and may be pushed downward.

The inside of the upper end of the shield 1 is provided with two notches 14 opposite one another. When the arms 3 are released from the 100 shield they will enter these notches and prevent the frame from turning in relation thereto. When the arms spread apart they will rest against the end of the shield 1 and will prevent the shield 1 from being moved upward until 105 the arms have been again compressed.

The arms 3 are provided with a series of small holes as shown in Figures 6 and 7, a lacing 16 is threaded through these holes and the edge of the net as shown in Figure 7. This form of lacing anchors the edge of the net to the inside of the arms so that it will not shift thereon. The cord connection 11 will also be threaded through the edge of the net before being attached to the arms 3.

10 This device is primarily intended for use of trout fishermen for landing a fish when caught on light tackle and also for use as a wading staff to assist the user in maintaining his balance when traveling on rough and slippery river beds or in rapid moving waters.

Operation.—In the event that the device is already in the hand, and it is desired to open the same, the user will rest the lower end 15 against the ground and will push, with the thumb, on 20 arm 3 so as to withdraw pin 12 out of the hole 13 and simultaneously push downward on shield 1 until it abuts against the stop 10, this action releases the arms and net and the arms automatically spread apart. To close the net, 25 the arms are compressed, with the net placed between, and the shield is pushed upward over the same until the pin 12 drops into the hole 13. It is the moving of the shield up and down which covers or uncovers the frame and 30 net and this movement of the shield does not substantially lengthen or shorten the device. This shield furnishes a long handle for the net when the same is uncovered and a handle or grip portion when the frame and net are enclosed and the device used as a wading staff.

It is thought that from the foregoing the construction, operation and advantages of my device will be clearly understood, but I reserve the right to effect such modifications thereof 40 as may come fairly within the spirit of the invention.

What I claim is:—

1. The combination in a device of the kind described, of a pair of normally diverging spring arms, a flexible connection between the arms, a net attached to the arms and connection, a shield for holding the above-mentioned parts collapsed against the tension of the arms and a projection on one of said arms engageable with a seat of said shield to latch the parts in collapsed position, said shield, upon release of said latch, being longitudinally movable to release the arms and thereby spread the net.

45 2. The combination in a device of the kind described, of a pair of diverging spring arms, a flexible connection between the arms, a net at-

tached to the arms and connection, a shield for holding the above-mentioned parts collapsed against the tension of the arms and confined therein, a lock for preventing movement of the shield, release of the lock permitting movement of the shield and movement thereof releasing the arms, such releasing permitting the arms to automatically open and spread the net.

3. In combination, a net frame consisting of two diverging spring arms and a flexible connection between the same, a net attached to the frame, a core into which the arms are fastened and provided with an extension, a stop on said extension, and a shiftable covering for the net frame and a portion of the extension, movement 85 of the covering against the stop releasing the net frame so that the arms thereof will automatically spread apart and thus spread the net.

4. The combination in a device of the kind described of a staff, a pair of normally diverging spring arms attached to and extending beyond said staff, a net attached to said arms, a sheath adapted to confine said arms in collapsed condition against their spring tension, said sheath being shiftable along the staff to release 95 the arms progressively from their diverging to their attached ends.

5. The combination in a device of the kind described of a staff, a pair of normally diverging spring arms attached to said staff, a net attached to said arms, a locking projection on one of said arms, a sheath adapted to confine said arms in collapsed condition against their spring tension and shiftable along the staff to release the arms, means on said sheath coacting with 105 the locking projection when said sheath is in confining position to lock the arms and sheath against relative rotary movement, and means on said sheath coacting with the arms when said sheath is in released position to lock the arms 113 and sheath against relative rotary movement.

6. The combination in a device of the kind described of a staff, a pair of normally diverging spring arms attached to and extending beyond said staff, a net attached to said arms, a 120 sheath provided with recesses and adapted to confine said arms in collapsed condition against their spring tension, a projection on one of said arms engageable with a recess of the shield to latch the parts in collapsed condition, said 125 sheath being shiftable along the staff to release the arms and to engage them with recesses of said sheath to prevent relative rotation of the arms and sheath.
